E. F. HARDEY

MANICURING DEVICE

Filed April 19, 1926

Inventor:

Edwin F. Hardey,

By

F. G. Fischer,

Attorney.

Witness:

Bred L. Fischer.

UNITED STATES PATENT OFFICE.

EDWIN F. HARDEY, OF KANSAS CITY, MISSOURI.

MANICURING DEVICE.

Application filed April 19, 1926. Serial No. 102,964.

My invention relates to manicuring devices and one object is to provide a simple and inexpensive device of this character embodying means for trimming, filing and cleaning the finger nails.

A further object is to provide a device in which a guard is associated with the finger nail trimming blade to limit the entrance of said blade into the nail and thereby eliminate the danger of cutting the flesh.

A further object is to provide a device of this character which can be safely carried in the pocket when not in use.

In order that the invention may be fully understood, reference will now be had to the accompanying drawing, in which:

Fig. 1 is a perspective view of the device.

Fig. 2 is a longitudinal section of the device on line 2—2 of Fig. 3.

Fig. 3 is an irregular longitudinal section on line 3—3 of Fig. 2.

Fig. 4 is a detail plan view of a finger nail tool.

In carrying out the invention, I employ a hollow handle 2 which is preferably formed from one piece of sheet metal and has a longitudinal slot 4 therein. The two narrow sides 6 of the handle 2 are cut away at their rear portions to form openings 8 for the purpose of exposing the cutting edges 10 at the ends of a blade 12. The blade 12 extends transversely of the rear portion of the handle 2 and is arranged between the upper and lower portions 14 and 16 of said handle, suitable means such as a screw 18 being employed for clamping said upper and lower portions 14 and 16, respectively, firmly against the upper and lower edges of the blade. For further security the upper edges 40 of the blade 12 are set in corresponding recesses 15 and 17 in the upper and lower portions 14 and 16, respectively, of the handle, as shown by Fig. 2. The blade 12 is set inwardly from the rear and side margins of the upper and lower portions 14 and 16, respectively, so that said margins will constitute a guard 20 which will prevent either of the cutting edges 10 of the blade 12 from entering the finger nail far enough to cut the flesh.

22 designates a finger nail tool comprising a combination file and nail cleaner which is slidably mounted within the handle 2 and has a pointed forward end 24 whereby the nails may be readily cleaned. Said combination file and nail cleaner 22 slides in and out through an opening 26 in the forward end of the handle 2, from which, however, it is prevented from being withdrawn by a thumb piece 28 projecting outwardly from the rear portion of said tool 22 through the slot 4.

An elongated U-shaped spring 30 is arranged within the handle 2 to clasp opposite sides of the combination file and nail cleaner 22 and thus frictionally hold it at any point of its adjustment in the handle 2. The spring 30 is held from longitudinal movement in the handle 2 by abutting the screw 18 and the forward portion of said handle at opposite sides of the opening 26, as shown by Fig. 3.

In practice when the nails are to be trimmed, either margin of the guard 20 is slipped beneath the nail and against the flesh and thereby limits the entrance of the cutting edge of the blade 12 into the nail, so that there will be no danger of cutting the flesh. When the combination file and nail cleaner 22 is to be employed it is withdrawn from the handle 2 to the desired extent by pushing outwardly upon the thumb piece 28. When the combination file and nail cleaner 22 is in use the handle 2 forms a convenient means for holding said combination file and nail cleaner. When not in use, the combination file and nail cleaner 22 is pushed backwardly into the handle 2, see dotted lines Fig. 3, so that its point 24 will not project from the opening 26 and cut a hole while being carried in the pocket.

From the foregoing description it is apparent that I have provided a manicuring device embodying the advantages above pointed out, and while I have shown and described the preferred form and combination of parts, I reserve the right to all such changes and modifications as properly fall within the spirit and scope of the invention as claimed.

Having thus described my invention, what I claim and desire to secure by Letters Patent, is:

1. In a device of the character described, a hollow handle, an elongated U-shaped spring arranged within said handle, and a finger nail tool slidably mounted in said handle and having two longitudinal sides frictionally engaged by said spring.
- 10 2. In a device of the character described, a

hollow handle having a longitudinal slot, an elongated U-shaped spring arranged within said handle, a finger nail tool slidably mounted in said handle and having two longitudinal sides frictionally engaged by said spring, and a thumb piece fixed to said finger nail tool and projecting through the slot in the handle.

In testimony whereof I affix my signature.

EDWIN F. HARDEY.
